Primary Examiner — Khawaja Anwar(74) *Attorney, Agent, or Firm* — Patentfile, LLC; Bradley C. Fach(57) **CLAIM**

The ornamental design for an audio connector, as shown and described.

DESCRIPTION

FIG. 1 is a front perspective view showing the new, original, and ornamental design of an audio connector;

FIG. 2 is a front elevation view thereof, the rear side being a mirror image;

FIG. 3 is a right side elevation view thereof, the left side being a mirror image;

FIG. 4 is a bottom side plan view thereof; and,

FIG. 5 is a top side plan view thereof.

The broken lines shown in the drawings represent environmental subject matter and form no part of the claimed design.
